DEVICE FOR REMOVING SHAVINGS IN
SOUND RECORDING MECHANISMSGustav Fries, Cologne, Germany, assignor to Tefi-
Apparatebau Dr. Daniel K.—G., Cologne, Ger-
manyApplication August 25, 1937, Serial No. 160,734
In Germany August 28, 1936

3 Claims. (Cl. 198—214)

This invention relates to a device for removing the shavings formed in sound recording mechanisms, in which the sound recording is effected on the record carrier by the shaving of the outer surface thereof to form grooves.

In such mechanisms it is important to remove the shaving formed on the cutting as carefully as possible. Particularly as far as mechanisms employing endless film bands are concerned on which uninterrupted recording for some hours is possible, the removal of the shaving is essential for safety in operation, since the shaving easily winds itself around all rotating parts and thus gives rise to severe disturbances.

It is known to clear away the shaving by winding it on rollers arranged laterally of the film path or on rollers rotating above the sound record carrier. In these arrangements the shaving or cutting must, however, be fed uninterruptedly to the rollers as, if it once tears, it will not automatically again be wound on the rollers. Tearing of the shaving cannot be avoided when such rollers are used for the reason that the quantity of shaving arriving at the rollers is always constant, while the circumferential speed increases with the amount of the shaving rolled thereon. Furthermore, tearing of the shaving can take place also for other reasons, for example with endless film bands at the point of junction.

The principal object of this invention is to overcome the above disadvantages in a simple and sure manner and to this end, according to the invention, a worm is provided for taking and removing the shaving, which rotates in a guide tube fitted with internal longitudinal ribs or grooves. The shaving cut from the sound record carrier is seized by the worm and first rolled onto one of the spirals until the latter is filled with shaving. When the shaving roll has attained a certain thickness, it is forced against the longitudinal ribs of the tube, whereby it is prevented from further rotation. As the worm, however, continues to rotate uniformly, longitudinal displacement of the wound shaving is then effected within the guide tube, until the shaving finally emerges in uninterrupted sequence from an opening formed in the tube after the manner of a roll of hair curls.

In order to facilitate longitudinal displacement of the roll of shaving on the worm, the latter is formed with a pitch and thread depth which increase toward the end. In this way the roll is gradually loosened, so that its longitudinal displacement on the worm is possible without great expenditure of force.

In a further embodiment of the invention, teeth are arranged on the part of the worm lying within the area of the inlet opening of the guide tube, which automatically seize and wind the shaving on the worm even after it has been torn. The worm is preferably disposed, together with the guide tube, closely above the sound record carrier behind the cutting stylus, and the shaving is, in this case, fed on the sound record carrier itself to the worm. It is further obviously advantageous, in this case, to arrange the worm with the guide tube so that it is detachable from the sound record carrier.

By way of example, the invention is illustrated in the accompanying drawing, in which Figure 1 is a longitudinal section of the shaving clearing device and Fig. 2, a cross section thereof.

Referring to the drawing, immediately above the film band 10 serving as sound record carrier a guide tube 2 is arranged transversely to the direction of motion of the carrier. In a suitable bearing at one end of the tube 2 a worm 1 is rotatably mounted and so constructed that its pitch and thread depth increases from the bearing end to the free end. In the guide tube 2 a recess 14 is formed having a width corresponding to that of the film band 10, so that the shaving can reach the worm from any part of the film band. On the worm portion within the limits of the recess 14 teeth 15 are provided which immediately seize and wind the shaving around the worm as it arrives in the guide tube 2. In the guide tube 2 a series of longitudinal ribs 3 are disposed between which grooves 16 are formed. The drive of the worm is derived from the shaft 5 through the pinion gears 6, 7, 8, 9, whereby the worm receives the correct direction of rotation and the correct speed.

The shaving clearing device operates in the following manner:

A shaving 13 is cut, during recording, from the film band 10, at a very small distance beneath the guide tube 2, by the cutting stylus 11 which is controlled by an electro-acoustic box 12. The shaving 13, which curls up when cut by the stylus 11, is taken along by the moving film band 10 and thus comes in front of the inlet opening 14 formed in the guide tube 2. Here it is seized by the teeth 15 disposed on the worm 1 and wound first around one thread turn. This continues until the rolled quantity of shaving has become so large that it enters the grooves 16 and is held by the longitudinal ribs 3. The roll of shaving now no longer rotates, but commences to move forward due to the continued rotation of the 55

worm 1 and is removed. As the pitches of the worm are greater and deeper towards the end, a loosening of the shaving roll simultaneously results which greatly assists in the removal thereof without the necessity for the use of any great force. The guide tube 2 is widened at its continuation beyond the longitudinal ribs 3, whereby the removed shaving is easily conducted forward by the subsequent batches until it falls out at the end of the tube in the form of wound 10 curls 17.

Obviously the shaving clearer according to the invention is suitable not only for such recording mechanisms which operate with film bands as 15 described, but also for mechanisms in which sound record plates are employed or any similar devices in which, during recording, a continuous shaving is produced.

I claim:

- 20 1. A device for removing thread-like shavings produced during sound recording, said device comprising a tube having a slot formed therein for receiving the shavings, a worm within said tube, means engaging one end of said worm for rotatably supporting the same, means connected with said end of the worm for rotating the worm to cause it to seize shavings received through said slot and feed them along the tube for discharge at a remote point, and a plurality of longitudinal 25 ribs carried by the inner walls of said tube, the excess shavings extending into grooves formed between said ribs.

2. A device for removing thread-like shavings produced during sound recording, said device comprising a tube having a slot formed therein for receiving the shavings, a worm within said tube, means engaging one end of said worm for rotatably supporting the same, means connected with said end of the worm for rotating the worm to cause it to seize shavings received through said slot and feed them along the tube for discharge at a remote point, the pitch and the thread depth of said worm decreasing toward said end thereof, and a plurality of longitudinal ribs carried by the inner walls of said tube, the excess shavings extending into grooves formed between said ribs. 5 10

3. A device for removing thread-like shavings produced during sound recording, said device comprising a tube having a slot formed therein for receiving the shavings, a worm within said tube, teeth carried by that portion of the worm which is situated opposite said slot, means engaging one end of said worm for rotatably supporting the same, means connected with said end of the worm for rotating the worm to cause it to seize shavings received through said slot and feed them along the tube for discharge at a remote 20 25 point, and a plurality of longitudinal ribs carried by the inner walls of said tube, the excess shavings extending into grooves formed between said ribs. 25
